**DEVICE FOR DRIVING THE PLATEN OF A
TYPEWRITER**

Enzo Ascoli, Yverdon, Switzerland, assignor to Paillard S. A., Sainte-Croix, Switzerland, a corporation of Switzerland

Application May 21, 1956, Serial No. 586,306

Claims priority, application Switzerland July 5, 1955

1 Claim. (Cl. 197—114)

The rotatable driving of the platen of a typewriter is effected by means of a line spacing mechanism, controlled either manually, by the line spacing lever, or electrically. These movements of rotation impart accelerations to the sheets of paper passing around the platen, at the commencement of each movement, and decelerations (negative accelerations) when stopping against stops.

The forces of acceleration thus created are opposed by frictional forces present between the sheets and the platen and between the sheets and the interposed carbon sheets, so as to prevent a possible slipping of the sheets relatively to the platen, or between said sheets. It is obvious that when the forces of acceleration exceed the frictional forces, said slipping becomes unavoidable, as a result of which a defective movement of the paper occurs.

The frictional forces depend, on the one hand, on the pressure occurring between the sheets and the platen, and between the sheets themselves, and on the other hand, on the coefficients of friction. Whilst the pressure, which depends on the driving rollers, is controlled easily, this is not the case as regards the coefficients of friction which vary with the quality of the paper, as also with the temperature, humidity and so forth.

On the other hand, the forces of acceleration vary, in the case of manual typewriters, from one user to another, which renders their control difficult.

Amongst the vertical forces of acceleration, due to angular movements of the platen, horizontal forces are also due to the movements of the carriage. However, the action of said latter is more effectively overcome, in particular by the friction between the driving rollers and the papers, said friction in the vertical direction being replaced by a much weaker resistance to rolling.

But, as is well known, the value of frictional resistance (at rest) decreases rapidly when, as a result of the movement, it is converted into sliding friction. Thus, when the sliding movement of the paper is reduced by the action of vertical forces of acceleration, the horizontal forces of acceleration may produce a horizontal sliding, even

2

when by themselves, they are not capable of doing this.

From the foregoing it will be seen that it is indispensable, for the correct movement of the paper, to maintain the vertical forces of acceleration, due to angular movements of the platen, below the value which can cause a slipping of the paper.

The subject of the present invention is a driving device for the platen of a typewriter, comprising a line spacing mechanism, characterised in that the said mechanism is connected to the platen by means of a resilient coupling adapted to deaden the shocks at the beginning and stopping of each angular movement of the platen, in such a manner as to reduce the forces of acceleration acting on the paper.

15 One form of construction of the device according to the invention is shown diagrammatically and by way of example in the accompanying drawing.

The platen 1, provided at each of its ends with a hub 2, 3, respectively, is mounted on a shaft 4 turning in bearings 5 and 6 provided in the chassis of the carriage of a typewriter (not shown). The platen 1 is secured angularly to the shaft 4 solely at one of its ends, particularly by the hub 3, by means of screws 7. The other end of the platen, particularly the hub 2, can turn freely on the shaft 4. A ratchet wheel 8, forming part of the line spacing mechanism, is secured near the end of the shaft located opposite its point of securing to the platen.

To each of the ends of the shaft 4 is secured an operating knob 9, 10, respectively.

20 It will be readily understood that, when the driving of the platen in rotation is effected through the medium of the line spacing mechanism (wheel 8), the shaft 4 operates in the manner of a torsion bar, so that it constitutes an elastic clutch between the said mechanism and the platen, enabling the shocks, at the starting and stopping of each angular movement of the latter to be deadened and, consequently reducing the forces of acceleration acting on the paper.

I claim:

25 40 In a typewriter, means for rotatably driving a platen and controlling undesirable movement thereof comprising, a resilient, axially disposed shaft passing through said platen; a line spacing mechanism connected to said shaft at one end thereof, said platen being rigidly secured to said shaft at the end opposite said line spacing mechanism, and being freely rotatable on said shaft at the end adjacent said line spacing mechanism, whereby said shaft acts as a torsion bar to control the shocks resulting from the actuation of said line spacing mechanism and thereby avoids inaccurate line spacing.
